UNITED STATES PATENT OFFICE

CHARLES P. MINNING, OF LOS ANGELES, CALIFORNIA

STRUCTURE FOR REFRIGERATORS AND OTHER DEVICES

Application filed April 15, 1931. Serial No. 530,220.

My invention relates to improvements in structures for refrigerating means and other uses; and particularly to a novel and superior structure enclosing a chamber wherein perishable articles can be stored for preservation at a given point, or for shipment to places at a distance. Preferably the invention is embodied in a refrigerator car; but obviously the same principle can be followed in the building of stationary refrigerators.

The refrigerator cars of familiar design are constructed principally of wood, mounted on a standard chassis or truck. They are reinforced with steel rods and angles for strength and stability and lined with different insulating materials, such as paper, felt, cork and others, between outer and inner wood walls; thus providing central air spaces, the whole being about seven inches thick.

In such a refrigerating car it is often difficult and always expensive to keep the contents at the desired temperature and frequent re-icing and consequent loss of time en route, are unavoidable. These cars are easily damaged by rough usage, and are exposed to different climatic conditions and wide and sudden changes of temperatures, while being hauled across the country. Under these conditions wood will often shrink and warp, causing joints to open and allowing outside air and moisture to enter and search out apertures and small crevices in the different interior layers of insulating materials, which have no continuous unbroken surface. The air in the air spaces above mentioned, can and will now circulate, thereby destroying their usefulness.

Confined air, not in a state of circulation is a well known low conductor of heat but when this air starts to flow it causes the ice to melt quickly and makes frequent examination and replenishing of ice necessary.

Virtually all insulating materials to which I have previously referred are fibrous and their capillary action, making them absorb moisture, is well known. Moisture and water are good conductors of heat; they not only reduce the insulating qualities of the different materials in a refrigerator car, but they also cause rot, mold and disintegration,

thereby creating unsanitary conditions, which will attract rodents and other vermin. These materials, further, have no structural strength and generally give rise to a fire hazard; besides the usual method is to precool the goods to be shipped, and the function of the refrigerator law is to keep them in a cool condition. The amount of ice required to do this, depends greatly on the quantity of outside heat, that can penetrate to the inside of the car. Existing refrigerator cars with constant attention and most skillful workmanship, are subject to great infiltration of air and moisture, requiring periodic repairs at great expense and loss of time, and consequent high operating cost, and give only a short life of the equipment at best.

An object of my invention is to provide a refrigerator car not of several materials, but substantially of one material, which is of great strength and durability, with an ideal physical composition of low density (porous) and low thermal conductivity, non-absorbent (moisture proof)—and essential quality—permanent and stable in condition, not liable to swell, shrink or disintegrate, sanitary and vermin-proof, practical and capable of being easily constructed by ordinary workmen. It is also an excellent fire retarder and contains nothing to burn; can be produced and operated at a low initial and maintenance cost and is equally serviceable and adaptable for high, moderate or low temperatures in practice.

To build this refrigerator car the customary standard truck or chassis is used and mounted thereon is a skeleton steel framework with bars and braces and other suitable light iron rods and spacers, tied at the corners and having the approximate outside and inside dimensions of the car. On this frame with an air space between outer and inner wall, the top, bottom, sides and ends of the car are formed.

The nature and merits of the invention are fully set forth in the following description taken with the drawings which illustrate the body of a refrigerating car according to my invention. I of course reserve the right to make changes in various details without go-

ing beyond the principle of the invention or exceeding the scope or spirit of the appended claims.

On said drawings:

5 Figure 1 is a side elevation partly broken away, showing in outline the framework of the body of a refrigerator car in which the features of my invention are incorporated.

10 Figure 2 is a horizontal cross section taken on the line 2—2 of Figure 1 showing the manner in which the side walls and ends of the car are made.

15 Figure 3 is a vertical cross section on the line 3—3 of Figure 1, showing further how the bottom, side walls, and roof are constructed.

20 Figure 4 is a detail showing how the framework of the bottom, roof, sides and ends of the car is put together.

25 Figure 5 shows how the walls of the car are formed.

Figure 6 shows a corner of the complete wall.

25 Figures 7 and 8 show nettings of unequal mesh employed in forming the walls.

30 The same numerals identify the same parts throughout.

35 The body of the car may have the same shape as the body of the ordinary refrigerating car now in use. In my invention, however, I build a framework comprising an outside cage 1 and a smaller inside cage 2 within the outside cage and on each of these cages is a complete covering of metallic netting indicated at 1a on the outside cage and 2a on the inside cage. The size of

40 the mesh of this netting may be about half an inch. The dimensions of the two cages will be such that the two nettings 1a and 2a will be about 7 inches apart. Between these

45 nettings and likewise hung upon the inner and outer cages, is a pair of nettings 1b and 2b, the former being separated about 3 inches from the netting 1a and the latter the same distance from the netting 2a; so that

50 throughout their extent there will be a space between nettings 1b and 2b about one inch thick. This space is indicated at 3. Preferably the size of the mesh making up the

55 netting 1b and 2b is $\frac{1}{4}$ inch, or about half the mesh of the nettings 1a and 2a supported by the inner and outer cages. The framework and the four nettings above mentioned will extend over all six sides of

60 the car body, that is the bottom, roof, sides and ends; and the spaces between the nettings 1a and 1b, and 2a and 2b will be filled with a monolithic composition, introduced

65 in plastic condition, that will set and harden and form a rigid mass. This material is shown at 4. The body of the car may be

60 provided with an opening 5 in one side and it may likewise have the usual trap door in the roof for ice storage. The wheels and

70 rails are indicated diagrammatically at band 7 in Figure 1.

75 The material indicated at 4 is a monolithic aggregate produced by taking raw cinders

70 from locomotives or other power plants and crushing and screening the cinders so that

75 they are not over $\frac{1}{16}$ of an inch in length, breadth or thickness, their modulus finesse

70 being approximately 40. These cinders are

75 then put into a concrete mixer and Portland cement added in the proportion of 6 or 7

parts of cinders to one of cement by volume.

80 After intermingling I pour enough water to wet the mass enough so that it will not run or slump; and then by means of compressed air and a cement gun, the aggregate

85 is blown in through the screens 1a and 2a, which easily permits the composition to pass

80 and enter because the mesh of the screens 1a

85 and 2a is greater than the largest dimension

80 of the cinders. The inner screens 1b and 2b,

85 however, are of smaller mesh than the largest dimension of the cinders and these arrest

80 and hold the aggregate so that the space 3

90 is not entered. The composition must be

95 packed in well and thus the car body when

90 finished comprises inner and outer walls,

95 layers or shells with the air space 3 between

90 them. When the mass sets it takes a light

95 gray color and because the two shells are

90 separated with a space 3, the inside of the

95 car is very effectively insulated against the

90 entrance of heat. Likewise the body of the

95 car is without joints or crevices; and the

100 air space, being entirely enclosed, permits

no circulation therein.

In some instances a refrigerator construction

105 may be built to include only a single wall instead of a double wall with an air

100 space therein. In that case I shall have to

105 use only an outer netting 1—a and an inner

110 netting of small mesh 1—b, with the necessary

115 frame to support these nettings; and the

120 plastic mixture is put on in the same

125 way as before by forcing it through the outer

120 wall of larger mesh. The wall is finished by

130 putting on the outside coating as before.

To form the outside cage I may employ

115 angle bars at the corners indicated at 8, trans-

110 verse angle bars at the ends indicated at 9

115 and longitudinal angle bars for the sides in-

120 dicated at 10. These bars may be braced

125 and tied by vertical, horizontal and diagonal

120 reinforcing rods 11 for the bottom, top, sides

125 and ends; and the inner cage 2 may be sim-

130ilarly constructed. The netting 1a is spread

135 and fastened over the six faces of the outer

130 cage so as to be continuous and so is the net-

135 ting 2a on the inside cage 2. I also employ

140 for the purpose of spacing the quarter inch

145 wire nettings 1b and 2b the proper distance

140 from each other, and from the nettings 1a

145 and 2a, a number of bolts of the required

150 length to extend from the outside cage to

155 the inside cage, as indicated at 12. These

160

bolts (see Figure 5 will carry clips or spacers 13 which are U-shaped approximately 3 inches long with perforated arms so that the bolts can pass through them. These bolts 5 have heads and suitable perforated plates or washers 14 may be employed to cooperate with the heads and engage the outer face of the netting 1a for example. Similar plates engage the netting 2a and when the nuts 15 10 are attached, the bolts are secured in position. The spacers 13 will thus keep the nettings 1b and 2b properly spaced from the larger mesh nettings and spacers 16 may be employed on the bolts 12 between the nettings of quarter inch mesh if desired. The nettings 1b and 2b may also be supported upon frames made up of vertical angle bars 17 and horizontal transverse and longitudinal bars 18 which may be reinforced by 20 rods similar to the rods 11, if necessary. The nettings 1a and 2a will of course be secured to the angle bars and reinforcing bars 11 at as many points as required to prevent sagging or bulging and the same procedure will 25 be followed with the nettings 1b and 2b with respect to the bars or rods for holding them; so that the bolts 12, spacers 13 and 16, and plates 14 suffice to hold the nettings spaced the exact distance apart over their entire extent. If desired also the four nettings can 30 be supported by additional means, as by putting supports under the angle bars 9 and 10 of the inside shell at the bottom and thus taking the weight as much as possible off 35 the bolts 12 at the top sides and ends of the car. The inside and outside cages may also at their corners be connected by diagonal rods or wires 19 uniting the junction points of angle bars 9, 10 and 11 and the air space 40 or pocket 3 may be divided up into several sections or pockets by putting in enough cement to fill the air space in the vertical corners at the ends of the car and the horizontal corners along the top and bottom as indicated at 20.

To form the door space I may use vertical rods 21 at the proper points and the horizontal rod or bar 22 with diagonal reinforcing rods or braces 23 similar to the rods 11 above the opening. Reinforcing angle pieces 50 may be employed if desired at the ends of the braces 23, and elsewhere if desired at the ends of the bars 8, 9, 10 and rods 11. When the cement and cinders have set and 55 hardened, the inside and outside faces of the walls of the bar are given a finishing coat 25 by taking cinders which are crushed as fine as sand mixed with cement in the proportion of four parts of cinders to one of cement by volume, treated with slightly more water and then put on so as to form a covering about one-half an inch thick. The pores of the walls of the car are thus closed, giving a smooth, even surface, impervious to 60 water. The spaces between the nettings 1a

and 1b, 2a and 2b, as well as between the inside nettings 1b and 2b around the door opening 5 are of course filled up so that the air space is closed at all points.

For the sake of clearness, no attempt is 70 made to show the rods 11 in Figures 2, 3 and 6, and on these three views and Figure 1, the bars 8, 9, 10 are indicated in part only.

The body of the car is therefore comparatively light in weight and of great strength, 75 an efficient insulator and entirely leak proof. The metallic framework or caging will prevent cracking and breaking at any point.

Some of the properties of a car constructed 80 in this manner of one material, besides its inherent strength, may be enumerated as follows: The car is of low density, being porous, and low thermal conductivity. It is non-absorbent and proof against moisture and water. Its condition is permanent because 85 in no part will it swell, shrink, crack, spall or disintegrate; it is sanitary, offers no lodging to vermin and can be washed with a hose. It is easily constructed and can be built by 90 ordinary workmen; it is fire-proof and costs practically nothing to maintain; it will not be affected by sudden and extreme changes in temperature. It will stand very rough usage without impairing its efficiency. It 95 is entirely enclosed and will prevent infiltration of air. It is adaptable for sharp freezing at low temperatures and in case of fire its contents will be protected and preserved in a manner which cannot be done with present 100 construction. With this car body goods will not be influenced by any change in temperature, even in case of fire, because temperatures of 400° have been found to have no influence on the interior. A car body of this 105 description can be built for permanent mounting on the truck of an ordinary car or it can be built as a separate unit and mounted temporarily on a flat car, leaving the flat car available for use at other times without the refrigerator.

It makes no difference what kind of refrigerant is used, whether water, ice or frozen carbon dioxide; and if the latter is employed 115 low temperatures can be obtained for shipping goods that are frozen outright. This kind of refrigeration is now in the experimental stage and results so far have been poor on account of inadequate equipment.

This car can be constructed at a saving of 20 120 to 30% over present costs. The mixture of cinders and cement will readily take and hold nails and screws without cracking. It is also electrically non-conducting and acid-proof. I can also use this type of construction for 125 passenger cars because the walls will take any kind of finish and decoration. The material is even to some extent flexible and resilient. It will withstand severe stresses even if made up with reinforcements into the 130

shape of a railroad tie or sleeper and placed in road beds to hold rails.

I can of course use my invention not merely for making refrigerator cars but also in the same way to construct refrigerating chambers for ships, packing houses and homes. It is especially valuable for use on ships. I might add that a composition of this sort of cinders and cement is excellent for the purpose of fire-proofing steel girders and beams in buildings, elevator shafts, etc., and walls which are to be rendered fire-proof. It has no mortar joints to open and crack under the stress of heat. It is excellent for backing fire-brick in smelters and furnaces so as to prevent heat radiation; also to cover boilers. Another important characteristic is that it transmits sound very poorly and it can therefore be employed for talking picture studies, theatres and auditoriums, telephone booths, partitions, walls and bulkheads on ships.

If used for passenger cars, the surfaces can be finished in any kind of colors by mixing pigments with the finishing coating and this coating ground smooth and polished so as to appear like marble or stone. Designs can be traced upon the coating or it can be painted; and fixtures and trim are easily secured to the surfaces because nails and screws hold very readily without damaging.

The invention is thus of considerable importance in the building of walls and partitions for structures which are intended for other uses than refrigeration. Obviously, with a method as above described involving the nettings of unequal mesh so that a plastic can be forced through netting of larger mesh and stopped by the smaller, a wall or partition can be very readily and inexpensively erected.

I have found that railroad ties constructed by this process are very practical and almost indestructible. They will give results not obtainable with sand and gravel concrete ties because they are strong, tough and resilient and will withstand stresses that would break the ordinary brittle concrete tie.

Having described my invention what I believe to be new and desire to secure and protect by Letters Patent of the United States is:

1. A structure comprising inner and outer nettings, intervening separated nettings of smaller mesh than the inner and outer nettings and continuous cementitious material between the inner and outer nettings and the intervening nettings, making layers with air spaces between the intervening nettings.

2. A structure comprising inner and outer nettings, means for supporting the same, intervening nettings, spacing and holding elements for the intervening nettings attached to the inner and outer nettings, said intervening nettings being of smaller mesh than the outer nettings and cementitious material

forming inner and outer layers secured to said nettings.

3. A structure comprising inner and outer nettings, means for supporting the same, intervening nettings, spacing and holding elements for the intervening nettings attached to the inner and outer nettings, said intervening nettings being of smaller mesh than the outer nettings and cementitious material forming inner and outer layers secured to said nettings, said layers being cemented together at the corners thereof.

4. The method of building a structure which consists in supporting two nettings, of unequal mesh adjacent one another with a space between them, mixing cement with cinders of larger size than the netting of the smaller mesh and injecting the mixture into said space through the netting of the larger mesh.

5. The method of building a structure which consists in supporting two nettings of relatively small mesh between two other nettings of larger mesh, all of said nettings being spaced apart, mixing cement with cinders of smaller size than the nettings of larger mesh, injecting said mixture in opposite directions through the nettings of larger mesh against nettings of smaller mesh, and allowing said mixture to set to form a structure of two layers with an air chamber between them.

6. The method according to claim 5 in which the two outer faces of said structure are also given a finished coating of fine cinders and cement.

7. A structure comprising a pair of nettings, one being of larger mesh than the other to enable said structure to be formed by forcing a mixture of cement with cinders through the net of the larger mesh against the netting of smaller mesh, said mixture filling the space between the nets and being retained thereby.

8. A structure comprising a wall made of two nets in substantially parallel position, one of the nets being of larger mesh so that the structure can be formed by forcing a mixture of cement and cinders through the net of larger mesh, said mixture filling the space between the nets and making the structure continuous, and a finished coating of fine cinders with cement on one face of said structure.

Signed at Los Angeles in the county of Los Angeles and State of California this 26th day of January A. D. 1931.

CHARLES P. MINNING.
